UNITED STATES PATENT OFFICE.

CARL E. JOHNSON, OF ST. PAUL, MINNESOTA.

WATER-JACKETED VALVE-CAP AND SPARK-PLUG.

1,253,043.

Specification of Letters Patent.

Patented Jan. 8, 1918.

Application filed June 1, 1917. Serial No. 172,218.

To all whom it may concern:

Be it known that I, CARL E. JOHNSON, a citizen of the United States, residing at St. Paul, in the county of Ramsey and State of Minnesota, have invented certain new and useful Improvements in Water-Jacketed Valve-Caps and Spark-Plugs, of which the following is a specification.

This invention relates to a water jacketed valve and spark plug cap for engine cylinders, and is designed especially for use with gas engines employed in connection with farm tractors, though adapted to any explosive engine. But in tractor work the steady running of the engine through the entire day makes it essential to provide more than the usual means for keeping the valves and plug cool, to prevent burning out and sticking.

20 A further object of the invention is to provide firmness in the cap by increasing its bearing surface on the cylinder end, and this is secured by joining it to the cylinder along an oblique line instead of at a right angle to the piston rod, and by sloping this angle or line of juncture inwardly toward the valve side of the cylinder I bring the water jacket of the cap closer to the valves than would otherwise be the case, thereby 25 securing both firmness in the cap and cooling the valves by means of this formation of the cap and its jacket.

In the accompanying drawings:—

Figure 1 is a longitudinal section through the cylinder end adjacent the cap and through the cap, the piston and one valve being shown in elevation.

Fig. 2 is a section on the line 2—2 of Fig. 1.

40 Fig. 3 is an enlarged plan view of the cylinder head, the cap being removed.

The device can be adapted for engines having any desired number of cylinders but for illustration it is shown as applied 45 to a single cylinder.

In the drawings 1 designates the cylinder wall, 2 the jacket wall and 3 the water jacket. A piston 4 works in the cylinder and in the inlet 5 is arranged the valves, one 50 indicated at 6, being shown.

Sleeves 7 are formed integral with walls

8 and 10 of the water jacket on the valve side of the cylinder, the wall 8 being the inner wall and forming also the wall of the gas intake 5. This wall slopes obliquely 55 with respect to the sleeves 7, which extend on each side of it, the sleeves extending entire across the water jacket 3 at this point. The valve rods 9 work through these sleeves and are provided with the usual exterior 60 springs 11.

The cap 12 joins the cylinder end on the oblique line 13 having its greatest thickness on the valve side, and contains a water jacket 14, which jacket entirely surrounds 65 the spark plug 16, the walls at this point being as thin as possible. The water outlet 15 leads from the cap on the side opposite the valves. Communication is effected between the jacket 3 and the jacket 14 by the 70 passages 17 and 18. The water inlet is shown at 19, and the course of the water through the jackets and around the valves and plug is indicated by the arrows.

This construction provides the maximum 75 amount of cooling for both the valves and the spark plug.

What I claim is:—

1. The combination with an internal combustion engine having a water jacket, of a 80 hollow valve and spark plug cap having its greatest thickness at the valve side, and having a line of juncture with said engine cylinder along a line oblique with respect to the longitudinal axis of the cylinder, and 85 the interior of the cap having communication with the water jacket of said engine.

2. The combination with an internal combustion engine, having a water jacket and jacketed valves, of a hollow cap having a 90 water jacket, said cap joining the engine cylinder on an oblique line, the water jacket of the cap having its greatest capacity adjacent the valves, and having an outlet opposite said valves, said water jacket of the 95 cap having free communication with that of the engine, and a spark plug carried by the cap and surrounded on the sides by the cap water jacket.

3. In an engine of the type described having a water jacket, valves and gas inlet, valve stem sleeves formed integral with the

walls of the jacket, the inner jacket wall being oblique with respect to the sleeves, and a hollow cap having an inclined inner face of juncture with said engine, thereby increasing the bearing surface of the cap and bringing the water space in said cap into proximity with said valves, said cap

having communication with the water jacket of the engine and having an outlet on the side opposite the valves, and a spark plug 10 carried by and passing through the water jacket of the cap.

In testimony whereof I affix my signature.

CARL E. JOHNSON.
